CALL-ON SIGNAL CONTROL

Robert Mills, Forest Hills, N. Y., assignor to The Union Switch and Signal Company, Swissvale, Pa., a corporation of Pennsylvania

Application July 17, 1942, Serial No. 451,255

8 Claims. (Cl. 246—3)

My invention relates to railway traffic controlling systems of the type employing direct line wires for the control of switches, and of the main signals which govern movement of trains across the switches.

One of the objects of my invention is to provide improved means for controlling the call-on signals over the same line circuit that is provided for the control of the main signals.

Another object of the invention is to provide improved means for indicating response of the call-on signals over the same line circuit that is employed to indicate the condition of the main signals.

A further object of the invention is to provide improved call-on signal control apparatus which is adapted for use in connection with switch and signal control systems now in use.

Another object of the invention is to provide improved call-on signal control apparatus for use in connection with a switch and signal control system of the type shown in Letters Patent of the United States No. 2,106,990, granted February 1, 1938, to Harry C. Vantassel.

In practicing my invention I employ means responsive to the direct current supplied over the signal control circuit to determine which of the call-on signals is to be cleared and to also establish a pick-up circuit for a stick relay which is picked up on the supply of alternating current over the signal control circuit. This stick relay when picked up establishes a stick circuit to maintain itself picked up as long as direct current is supplied over the signal control circuit, while it also establishes a circuit to clear the appropriate one of the call-on signals.

When a call-on signal is cleared, direct current of one polarity or the other is supplied over the signal indication circuit to energize one of the indication relays at the control point, while at this time energy is also supplied to a slow pick-up relay which when it picks up cuts off the supply of direct current to the control circuit and supplies alternating current thereto. This energy keeps the indication relay energized, while it also energizes a call-on indication relay which cooperates with the indication relays to indicate that one or the other of the call-on signals displays a proceed indication.

I shall describe two forms of signal control apparatus embodying my invention, and shall then point out the novel features thereof in claims.

In the drawings,

Fig. 1 is a diagram illustrating one form of apparatus embodying my invention, and

Fig. 2 is a fragmentary diagram showing a modified form of apparatus which I may employ.

5 Similar reference characters refer to similar parts in both views.

In most instances in the drawings the relay contacts are shown directly under the relay winding, but in some cases in order to simplify the drawings, relay contacts are shown separated from the relay winding and where this is done the relay with which the contacts are associated is identified by appropriate reference characters placed directly over the relay contacts.

10 Referring to the drawings, there is shown therein a stretch of railroad track having a main track and a siding or diverging track which is connected with the main track by means of a track switch W.

15 Traffic may move in either direction over the main track, while the rails of the track stretch may be divided by insulated joints into track sections in the customary manner.

Movement of traffic from left to right across 20 the switch W is controlled by a signal RH which has an upper portion A which governs movement of traffic along the main track; a middle portion B which governs movement of traffic from the main track across the switch into the passing siding; and a lower or call-on portion C.

Movement of traffic from right to left across 25 the switch W on the main track is governed by a signal LHA which has an upper portion A, and a lower or call-on portion C. Similarly, movement of traffic from the branch track to the main track is governed by a signal LHB which has an upper portion A, and a lower or call-on portion C.

This invention is directed particularly to the 30 control of the call-on signals and is not concerned with the control of the other signals or of the switch except insofar as the system of this invention is intended for use with a particular system for controlling the switch and the associated signals.

35 As pointed out above, the call-on signal control means provided by this invention is adapted for use particularly with the remote control system shown in Letters Patent of the United States No. 2,106,990 to Harry C. Vantassel.

40 In the system shown in the patent to Vantassel the switch and the signals are controlled by polarized relays WR and HR which are supplied with energy from a remote point over line wires, while the supply of this energy is controlled by a two position switch control lever 1,

45

and a three position signal control lever 2. The system of the Vantassel patent also includes means governed in accordance with the position of the switch and the condition of the signals for supplying energy to the line wires to provide at the control point indications of the position of the switch and the condition of the signals.

The manner in which the switch control relay WR controls the switch W is not a part of this invention and has been omitted in order to simplify the disclosure.

Similarly, the manner in which the signal control relay HR controls the main signals RHA, RHB, LHAA and LHBA is not a part of this invention and has been omitted in order to simplify the disclosure.

The switch W has associated therewith a polarized indication relay WP to which energy of normal polarity is supplied when and only when the switch is in its normal position, and to which energy of reverse polarity is supplied when and only when the switch is in its reverse position.

The signals have associated therewith repeater relays RRG, LRG and RAG which are governed in accordance with the aspects displayed by the signals. The relay RRG is energized when and only when all three portions of the signal RH are displaying stop indications, while the relay RAG is energized when and only when the upper portion A of the signal RH displays its stop indication. The relay LRG is energized when and only when the main and call-on portions of both signals LHA and LHB are displaying their stop indications.

The improvement provided by this invention includes relays RHR, LHR and COSR which cooperate as hereinafter explained to control the call-on signals, while a slow pick-up relay COP is provided to control the supply of signal indication energy to the line circuit leading to the office. The equipment at the office includes signal indication relays RGPR, LGPR and COK, and a coding device CT.

As explained in the Vantassel patent, both the office and the station are provided with a source of direct current in the form of a battery having a negative terminal N, a positive terminal B, and a common or center terminal C, while the center terminals C of the two batteries are connected together by a common wire.

The system of this invention makes use of alternating current which may be of any appropriate frequency and may be supplied from any suitable source. The terminal CX of this source is connected to terminal C of the batteries, and thus is connected over the common wire to both the office and station locations. The other terminal of the source of alternating current is designated BX.

A push button PB is located at the office and is interposed in the wire Y and controls the supply of alternating current to this wire.

Operation of equipment to control the switch and the main signals

The equipment is shown in the condition which it assumes when the switch control lever 1 is in its normal position and the signal control lever 2 is in its center or intermediate position.

As the switch control lever 1 is in its normal position, energy of normal polarity is supplied to the switch control relay WR over the circuit which is traced from terminal B of the office battery through the lever 1, wire 3, back contact 4 of relay HS, wire 5, back contact 6 of relay P,

wire X, back contact 9 of relay HR, wire 12, and winding of relay WR to terminal C. Accordingly, the neutral contacts of the relay are picked up, while the polar contacts of the relay occupy their normal positions so that the switch machine SM is controlled to maintain the switch in its normal position.

In addition, the contacts of relay WR establish the circuit to supply energy to the relay WK. This circuit is traced from terminal B over back contact 15 of relay HR, front neutral contact 16 and normal polar contact 18 of relay WP, normal polar contact 20 and front neutral contact 21 of relay WR, wire Y, push button PB, back contact 26 of relay P, wire 27, and winding of relay WK to terminal C. As energy is supplied to relay WK, its contact 29 is picked up, while the relay may have other contacts, not shown, which control indication lamps to indicate that the switch is in correspondence with the lever 1.

If the switch lever 1 is moved to its reverse position, energy of reverse polarity is supplied to the relay WR and it causes the switch to move to its reverse position and when the switch is in this position, the contacts of relays WP and WR again establish the circuit to supply energy to relay WK.

If the operator wishes to clear a main signal to permit a train moving from left to right to cross the switch, he may do so by moving the signal control lever 2 to its right-hand position. On this movement of the lever the contact 2b completes a circuit for relay HS, so that this relay picks up and its contact 33 establishes a stick circuit to keep relay HS energized as long as the lever 2 remains in its right-hand position, while contact 34 of relay HS establishes a circuit for the slow pick-up relay P. In addition, when relay HS picks up, its contact 4 cuts off the supply of energy to the switch control relay WR, while the supply of energy to this relay is additionally interrupted when the contacts of relay P pick up. The neutral contacts of relay WR now release and prevent movement of the switch, while its contact 21 interrupts the supply of energy to wire Y and establishes connection from this wire to the winding of relay HR and also to the relays RHR and LHR. At this time contact 29 of relay WK releases but relay HS is maintained energized by current supplied over its stick circuit including its own front contact 33.

When the relay P picks up, its contact 6 connects wire X to wire 45, and thus to relays RGPR and LGPR, while its contact 26 connects wire Y to wire 35 and thus to contact 2a. The relay HR is now energized by current of reverse polarity which is supplied over the circuit which is traced from terminal C through the winding of relay HR, wire 37, back contact 21 of relay WR, wire Y, push button PB, front contact 26 of relay P, wire 35, and contact 2a to terminal N. Accordingly, the neutral contacts of relay HR pick up, while the polar contacts of the relay move to their reverse position so that one of the signals RHA or RHB may be caused to display a proceed indication, the one depending upon the position of the switch.

If the signal control lever is moved to its left-hand position to clear a signal to permit a train moving from right to left to cross the switch, wire Y will be connected through contact 2a to terminal B of the source and energy of normal polarity is supplied to the relay HR over the

circuit which is traced from terminal B through contact 2a, wire 35, front contact 26 of relay P, push button PB, wire Y, back contact 21 of relay WR, wire 37, and winding of relay HR to terminal C. The neutral contacts of relay HR therefore pick up, while the relay polar contacts move to their normal position so that one of the signals LHAA or LHBA may be caused to display a proceed indication, the one depending on the position of the switch W.

When one of the main signals displays a proceed indication, one or the other of the signal repeater relays releases. If the signal RHA or RHB displays a proceed indication, the relay RRG will release, while if the signal RHA displays a proceed indication, the relay RAG will also release. If the signal LHAA or LHBA displays a proceed indication, the relay LRG will release.

On release of the relay RRG while the relay LRG is picked up, connection is established from terminal B of the station battery through back contact 50 of relay COP, back contact 51 of relay RRG, and front contact 52 of relay LRG to wire 44. At this time neutral contact 9 of relay HR is picked up and connects wire 44 to wire X so that energy is supplied over wire X, front contact 6 of relay P, wire 45, asymmetric unit Q1, back contact 54 of relay LGPR, and winding of relay RGPR to terminal C. Accordingly, the contacts of relay RGPR pick up and establish the circuit for lamp RGEK which is traced from terminal B through back contact 56 of relay COK, front contact 57 of relay RGPR, and lamp RGEK to terminal C. The lamp RGEK, therefore, is lighted to provide an indication that one of the signals RHA or RHB is displaying a proceed indication.

On release of the relay LRG its contact 52 establishes connection from wire 44 through back contact 58 of relay COP to the negative terminal N of the station battery. At this time energy is supplied to relay LGPR over the circuit which is traced from terminal C through the winding of relay LGPR, back contact 60 of relay RGPR, asymmetric unit Q2, wire 45, front contact 6 of relay P, wire X, front contact 9 of relay HR, wire 44, back contact 52 of relay LRG, and back contact 58 of relay COP to terminal N. Accordingly, the contacts of relay LGPR pick up and establish the circuit including back contact 56 of relay COK and front contact 61 of relay LGPR to light the lamp LGEK so that this lamp indicates that one of the signals LHAA or LHBA is displaying a proceed indication.

On subsequent restoration of the signal control lever 2 to its intermediate position the supply of energy to the relay HR is cut off and the neutral contacts of this relay release to prevent the display of a proceed indication by the main signals, while contact 9 of relay HR cuts off the supply of signal indication energy to wire X and connects wire X to relay WR to permit the switch to be moved if desired.

Under normal conditions on energization of the relay HR one of the main signals will be caused to display a proceed indication. However, as explained in the patent to Vantassel the main signals are governed by traffic or other conditions in the vicinity of the switch, and on energization of the signal control relay HR the signals may not respond to provide a proceed indication. The system of this invention provides means effective at such times to control the call-

on signals so that the appropriate one of these will display a proceed indication.

Control of call-on signals

- 5 When the operator wishes to clear one of the main signals governing movement of traffic from left to right, he moves the signal control lever 2 to its right-hand position, and, as explained above, energy of reverse polarity is supplied over wire Y and wire 37 to signal control relay HR, while energy is supplied over a branch of wire 37 through asymmetric unit Q3, and back contact 63 of relay LHR and winding of relay RHR so that the contacts of relay RHR are picked up.
- 10 Accordingly, contact 64 of relay RHR interrupts the circuit of relay LHR and establishes connection from wire 37 to one input terminal of rectifier Q4, while contact 65 of relay RHR interrupts one circuit for supplying energy to the red lamp R of call-on signal RHC and establishes a circuit to permit energy to be supplied to the holding winding of relay COSR on picking up of the contacts of that relay. At this time contact 67 of relay RHR establishes a circuit to supply energy to the yellow lamp Y of the call-on signal RHC on picking up of the contacts of relay COSR, while the red lamp R of signal RHC continues to be lighted by current supplied over back contact 69 of relay COSR.
- 15 At this time the contacts of relay LHR remain released and its contacts 79 and 81 maintain circuits to supply energy to the red lamps of signals LHAC and LHBC.
- 20 For purposes of illustration it will be assumed that the main signals RHA and RHB remain at stop even though the signal control relay HR is supplied with energy of reverse polarity. Accordingly, the signal repeater relays RRG and RAG remain energized and energy is not supplied over wires 44 and X to relay RGPR and the signal indication lamp RGEK remains dark so that the operator knows that the main signals did not respond to movement of the signal control lever.
- 25 If the operator now wishes to clear the call-on signal RHC, he may do so by depressing the push button PB. When this is done, the supply of direct current to the wire Y is cut off and terminal BX of the source of alternating current is connected through front contact 28 of relay P to this wire. The impulses of reverse polarity of this energy are supplied through the asymmetric unit Q3 to the winding of relay RHR and keep the contacts of this relay picked up, while the impulses of this energy of normal polarity are supplied through asymmetric unit Q5, front contact 64 of relay RHR, and rectifier Q4 to the pick-up winding of relay COSR so that the contacts of this relay pick up and its contact 72 completes the circuit including front contact 65 of relay RHR for supplying energy to the holding winding of relay COSR so that the contacts of this relay remain picked up after the push button is released and the supply of alternating current is cut off. The relay RHR is snubbed by a rectifier so that it is slow enough in releasing to remain picked up during the intervals in which the impulses of energy of normal polarity are supplied.
- 30 When the push button is released, the supply of alternating current over line wire Y is cut off, while direct current of reverse polarity is again supplied thereto and keeps the relay RHR energized so that its contact 64 maintains the circuit of the holding winding of relay COSR.

When the contacts of relay COSR pick up, its contact 69 interrupts the circuit which it controls for supplying energy to the red lamp R of signal RHC and establishes the circuit including front contact 67 of relay RHR for supplying energy to the yellow lamp Y of signal RHC so that this lamp is lighted to permit a train to move across the switch.

When the signal RHC displays a proceed indication, the supply of energy to relay RRG is interrupted and the contacts of this relay release so that its contact 51 establishes the circuit including back contact 50 of relay COP for supplying energy of normal polarity over wires 44 and X to relay RGPR so that the contacts of this relay pick up.

In addition, on release of the relay RRG a circuit is completed for supplying energy to the slow pick-up relay COP. This circuit is traced from terminal B through front contact 75 of relay COSR, front contact 76 of relay RAG, back contact 73 of relay RRG, and winding of relay COP to terminal C. The relay COP is of a type the contacts of which are slow in picking up so that they remain released subsequent to release of the contacts of relay RRG for a period which is long enough to insure that the contacts of relay RGPR will become picked up by the direct current supplied thereto.

When the relay COP picks up, its contact 59 cuts off the supply of direct current to wires 44 and X and connects the circuit of these wires to terminal BX of the source of alternating current. The impulses of this energy of normal polarity are supplied over the circuit traced above to relay RGPR and keep the contacts of this relay picked up, while the impulses of this energy of reverse polarity are supplied to the relay COK over the circuit which is traced from the terminal CX of the source of alternating current through one leg of the rectifier Q6, the winding of relay COK, another leg of the rectifier Q6, front contact 60 of relay RGPR, asymmetric unit Q2, wire 45, front contact 6 of relay P, wire X, front contact 9 of relay HR, wire 44, front contact 52 of relay LRG, back contact 51 of relay RRG, and front contact 58 of relay COP to terminal BX.

On the supply of energy to the relay COK its contacts pick up and contact 78 establishes a circuit to energize the coding device CT so that contact 79 of the coding device is opened and closed at a predetermined rate, while contact 56 of relay COK interrupts the circuit for supplying steady energy to lamp RGEK and establishes a circuit including contact 79 of the coding device CT for supplying energy to the lamp RGEK so that this lamp provides a flashing indication which informs the operator that the call-on signal RHC is displaying a proceed indication.

If the operator wishes to cancel the call-on signal, he may do so by moving the signal control lever 2 to its intermediate position. This opens contact 2a and cuts off the supply of direct current to relay HR and to relay RHR. On release of the contacts of relay RHR its contact 85 interrupts the circuit of the holding winding of relay COSR so that its contacts release and its contact 72 additionally interrupts the holding winding of relay COSR so that the relay will remain released until the push button PB is again depressed to cause alternating current to be supplied.

In addition, on movement of signal control

lever 2 to its intermediate position contact 2b interrupts the circuit of relay HS so that it releases and its contact 34 interrupts the circuit of relay P. The relay P also releases so that its contact 6 reestablishes the circuit for supplying energy to the switch control relay WR, its contact 26 prevents supply of direct current signal control energy to wire Y and connects wire Y to relay WK, while contact 28 of relay P interrupts the alternating current supply circuit to thereby prevent supply of alternating current to the wire Y if the push button PB is depressed while the signal control lever is in its intermediate position.

On release of the relays COSR and RHR the circuit of the yellow lamp Y of signal RHC is interrupted and the circuit of the red lamp R of this signal is established.

On release of relay COSR its contact 75 interrupts the circuit of relay COP, while when the signal RHC displays its stop indication, relay RRG is again energized and its contact 73 additionally interrupts the circuit of the relay COP and its contact 51 interrupts connection from wire 44 to terminal B of the station battery.

The equipment operates in a similar manner to permit control of the call-on signals LHAC and LHBC. When the operator wishes to clear one of the main signals LHAA or LHBA, he moves the signal control lever 2 to its left-hand position. When the signal control lever is in this position, contact 2b establishes a circuit for relay HS so that it picks up and establishes a stick circuit for itself, while it also establishes the circuit for relay P so that the signal lever contact 2a causes direct current of normal polarity to be supplied over wire Y to relay HR and over a branch of wire 37, asymmetric unit Q5, and back contact 64 of relay RHR to the winding of relay LHR and the contacts of this relay pick up.

When the relay LHR picks up, its contact 63 interrupts the circuit of relay RHR and establishes connection from wire 37 to one input terminal of rectifier Q4, while contact 70 of relay LHR establishes the circuit to supply energy to the holding winding of relay COSR on picking up of the contacts of that relay. Contact 70, when picked up, interrupts one circuit for supplying energy to the red lamp R of signal LHAC, but this lamp is maintained lighted at this time by energy supplied over the circuit established by back contact 75 of relay COSR.

In addition, when the contacts of relay LHR pick up, contact 81 interrupts a circuit for supplying energy to the red lamp R of signal LHBC, but this lamp is maintained lighted by energy supplied over the circuit including back contact 82 of relay COSR.

A polar contact 84 of the switch indication relay WP also controls circuits for supplying energy to the red lamps of the signals LHBC and LHAC so that the red lamp of the signal LHBC is maintained lighted as long as the switch is in its normal position, and the red lamp R of signal LHAC is maintained lighted as long as the switch is in its reverse position.

When the contacts of relay LHR pick up, its contact 85 is closed to permit energy to be supplied to the yellow lamp Y of signal LHBC or LHAC, depending on the position of the switch.

If the main signals fail to provide proceed indications after the signal control lever 2 is moved to its left-hand position, the signal repeater relay LRG will remain energized and energy will

not be supplied to relay LGPR, and the lamp LGEK will remain dark so the operator will know that the main signals remain at stop.

If the operator now depresses the push button PB, the supply of direct current to wire Y is cut off and this wire is connected through front contact 28 of relay P to terminal BX of the source of alternating current. The impulses of this energy of normal polarity are supplied to the relay LHR over the circuit previously traced for this relay, while the impulses of this energy of reverse polarity are supplied through the rectifier Q4 to the pick-up winding of relay COSR over the circuit which includes front contact 63 of relay LHR and asymmetric unit Q3.

The relay COSR now picks up and its contact 72 completes the circuit of the holding winding of relay COSR so that the contacts of the relay remain picked up after the operator releases the push button. When the operator releases the push button, the supply of alternating current is cut off while direct current of normal polarity is again supplied over wire Y to relays HR and LHR so that the contacts of relay LHR remain picked up and maintain the circuit of the holding winding of relay COSR.

As the contacts of relays COSR and LHR are picked up, contact 82 of relay COSR and contact 81 of relay LHR interrupt the circuits which they control for supplying energy to the red lamp R of signal LHBC, but as the switch is in its normal position, contact 84 of relay WP maintains the supply of energy to the red lamp of signal LHBC so this lamp continues to be lighted.

At this time contact 70 of relay LHR and contact 75 of relay COSR interrupt the circuits which they control for supplying energy to the red lamp R of signal LHAC and this light is extinguished, while the yellow light Y of signal LHAC is lighted by energy supplied over the circuit which is traced from terminal B through front contact 69 of relay COSR, front contact 85 of relay LHR, front neutral contact 87 and normal polar contact 88 of relay WP, and yellow lamp Y of signal LHAC to terminal C. The call-on signal LHAC, therefore, provides a proceed indication to permit a train on the main track to advance across the switch.

If when the operator pressed the push button to pick up the relay COSR the switch had been in the reverse position, contact 84 of relay WP would have maintained the supply of energy to the red lamp R of signal LHAC, while contact 88 of relay WP would have caused the yellow light Y of signal LHBC to be lighted so that this signal would provide a proceed indication to permit a train on the branch track to cross the switch.

When either of the signals LHAC or LHBC displays a proceed indication, signal repeater relay LRG releases and its contact 52 establishes connection from wire 44 through back contact 58 of relay COP to terminal N of the station battery so that energy of reverse polarity is supplied to relay LGPR over the circuit which is traced from terminal C through the winding of relay LGPR, back contact 60 of relay RGPR, asymmetric unit Q2, wire 45, front contact 6 of relay P, wire X, front contact 9 of relay HR, wire 44, back contact 52 of relay LRG, and back contact 58 of relay COP to terminal C. Accordingly, the contacts of relay LGPR pick up so that contact 54 interrupts the circuit of relay RGPR and establishes connection from wire 45 to an input terminal of rectifier Q6, while contact 61 establishes the circuit of lamp LGEK.

On release of relay LRG energy is supplied to slow pick-up relay COP over the circuit which is traced from terminal B through front contact 75 of relay COSR, front contact 76 of relay RAG, back contact 89 of relay LRG, and winding of relay COP to terminal C. After a time interval long enough to insure that the contacts of relay LGPR have picked up, the contacts of relay COP pick up and its contact 58 interrupts connection from wire 44 to terminal N and connects this wire to terminal BX of the source of alternating current.

The impulses of alternating current energy of reverse polarity supplied over wire 44 and wire X maintain the relay LGPR picked up, while the impulses of this energy of normal polarity are supplied through asymmetric unit Q1, front contact 54 of relay LGPR, and rectifier Q6 to the winding of relay COK. This relay now picks up and its contact 78 establishes the circuit of the coding device CT, while contact 56 cuts off the supply of steady energy to the lamp LGEK and establishes the circuit including contact 79 of the coding device CT for supplying energy to the lamp LGEK so this lamp provides a flashing indication to advise the operator that one of the call-on signals is displaying a proceed indication.

On subsequent movement of the signal control lever 2 to its intermediate position contact 2a cuts off the supply of direct current of normal polarity to wire Y, and thus to relays HR and LHR so that relay LHR releases and its contact 70 interrupts the circuit of the holding winding of relay COSR and this relay releases. In addition, on release of relay LHR its contact 85 interrupts the circuit for supplying energy to the yellow lamp of one of the call-on signals, while contacts 70 and 81 of relay LHR establish circuits for supplying energy to the red lamps of signals LHAC and LHBC, respectively, so that both of these signals display stop indications.

When relay COSR releases, its contact 75 interrupts the circuit of relay COP, while when the signals LHAC and LHBC both display stop indications, relay LRG is again energized and its contact 89 additionally interrupts the circuit of relay COP, while its contact 52 prevents the supply of direct current to wire 44 on release of the contacts of relay COP. As the supply of both alternating and direct current to wires 44 and X is cut off, relays LGPR and COK release and interrupt the circuits of the lamp LGEK and of the coding device CT.

55 *Construction and operation of modification shown in Fig. 2*

In Fig. 2 of the drawings there is shown a modified form of apparatus which I may employ to control the call-on signals. Except as hereinafter pointed out in detail the system of Fig. 2 is the same in construction and operation as that shown in Fig. 1 and only those portions of the system are shown in Fig. 2 as are essential to the understanding of this modification.

The system shown in Fig. 2 employs a transformer TA, the secondary winding of which is connected in series with the wire Y and is of relatively low resistance so that it does not substantially reduce the supply of direct current over this wire. One terminal of the primary winding of the transformer TA is connected to common wire C and thus to terminal CX of the source of alternating current, while the other terminal of this winding is connected to the movable contact of the push button PB. The movable contact of

the push button is biased to a position in which it short circuits the transformer primary winding and thus prevents inductive surges in the circuit of wire Y on changes in the polarity of the direct current supplied thereto. When the push button is depressed, its contact establishes connection with terminal BX of the source of alternating current if contact 28 of relay P is picked up.

The pick-up winding of the relay COSR is supplied with energy over wire Y through the transformer TB and a rectifier Q4, while connection from wire 37 to the primary winding of the transformer is controlled by neutral contact 90 of relay HR. A condenser K is included in series with the circuit of the primary winding of the transformer TB to prevent flow of direct current in this winding. The circuit of the holding winding of relay COSR is controlled by contact 72 of the relay and by contact 92 of relay HR.

The relays COSR and HR cooperate as herein-after explained to control the call-on signals, while the relay HR operates as explained in connection with the system shown in Fig. 1 to control the main signals.

When the operator desires to clear a signal to permit a train moving from left to right to proceed across the switch, he moves the signal control lever 2 to its right-hand position and causes relay P to be energized as explained above, while direct current of reverse polarity is supplied over line wire Y and back contact 21 of relay WR to the relay HR. Accordingly, the neutral contacts of relay HR pick up and its polar contacts move to their reverse positions to establish a circuit, not shown, to permit signal RHA or RHB to clear. If traffic or other conditions in the vicinity of the switch are such that these signals remain at stop, no indication will be returned to the office. The operator may now wish to clear the call-on signal RHC and to do so he presses the push button PB.

When the push button PB is depressed, alternating current is supplied to the primary winding of transformer TA and energy is induced in the transformer secondary from which energy is supplied over wire Y, back contact 21 of relay WR, wire 37, front contact 90 of relay HR, and condenser K to the primary winding of the transformer TB. The other terminals of the transformer windings are connected together through the common wire and one-half of the office battery. At this time alternating current is supplied to the winding of relay HR, but the impedance of this winding is so high that flow of alternating current therein is substantially prevented. In addition, at this time the supply of direct current to the winding of relay HR is maintained so the neutral contacts of this relay are maintained picked up.

On the supply of alternating current to the primary winding of transformer TB energy is supplied from the transformer secondary winding through the rectifier Q4 to the pick-up winding of relay COSR and the contacts of this relay pick up so that contact 72 completes the circuit including front contact 92 of relay HR for supplying energy to the holding winding of relay COSR. Accordingly, the contacts of relay COSR will thereafter remain picked up as long as relay HR is energized.

On subsequent release of the push button PB the supply of current over the wire Y to the pick-up winding of relay COSR is cut off, but the contacts of the relay are maintained picked up by the relay holding winding. The circuit of the relay holding winding is maintained by contact

92 of relay HR as direct current continues to be supplied to this relay as long as the signal control lever remains in its right-hand position.

When the contacts of relay COSR pick up, contact 69 interrupts the circuit which it controls for supplying energy to the red lamp R of signal RHC, while polar contact 93 of relay HR interrupts the circuit which it controls for supplying energy to this lamp so that it is extinguished. 10 When contact 69 of relay COSR is picked up, it establishes a circuit to supply energy to the yellow lamp Y of signal RHC. This circuit is traced from terminal B through front contact 69 of relay COSR, front neutral contact 94 and reverse polar contact 95 of relay HR, and lamp Y to terminal C. Accordingly, the yellow lamp Y of signal RHC is lighted and this signal authorizes a train to advance across the switch.

At this time reverse polar contact 93 of relay HR maintains the supply of energy to the red lamp R of signal LHAC, while reverse polar contact 96 of relay HR maintains the supply of energy to the red lamp R of signal LHBC so these signals both display stop indications after 25 relay COSR is picked up. Contact 84 of relay WP also establishes a circuit to supply energy to one or the other of these signal lamps depending on the position of the switch.

In addition, when the contacts of relay COSR are picked up, contact 75 establishes the circuit to supply energy to relay COP, as explained in connection with the system shown in Fig. 1, so that an indication is provided at the office that the call-on signal RHC is displaying a proceed indication.

When the operator wishes to cancel the call-on signal, he may do so by returning the signal control lever to its intermediate position. This cuts off the supply of direct current to relay HR and the contacts of relay HR release so that contact 92 interrupts the circuit of the holding winding of relay COSR and the contacts of relay COSR release. The yellow lamp Y of signal RHC is now extinguished and the red lamp of the signal is again lighted, while the signal indication energy transmitted to the office is cut off.

The equipment operates in a similar manner to control the call-on signals LHAC and LHBC. When the operator wishes to clear a signal to 50 permit a train moving from right to left to cross the switch, he moves the switch control lever 2 to its left-hand position and causes a circuit for relay P to be established so that its contacts pick up with the result that direct current of 55 normal polarity is supplied over wire Y to relay HR. Accordingly, the neutral contacts of relay HR pick up while the polar contacts of the relay move to their left-hand or normal positions so that a circuit is established to permit clearing 60 of one of the signals LHA or LHB. If traffic or other conditions are such that these signals both remain at stop, no indication will be sent to the office and the operator may wish to clear one of the call-on signals.

65 If the operator now depresses the push button PB, alternating current energy will be supplied over wire Y and back contact 21 of relay WR to transformer TB, and therefrom through the rectifier Q4 to the pick-up winding of relay COSR. 70 The contacts of relay COSR now pick up and contact 72 completes the circuit for the relay holding winding so that the relay contacts remain picked up after the operator releases the push button and the supply of alternating current is cut off.

When the contacts of relay COSR pick up, contact 69 interrupts the circuit which it controls for supplying energy to the red lamp R of signal RHC, but energy is supplied to this lamp over the circuit established by normal polar contact 93 of relay HR and signal RHC continues to provide its stop indication.

When contact 69 of relay COSR is picked up, it establishes a circuit controlled by contacts of the signal control relay HR and by contacts of the switch indication relay WP for supplying energy to the yellow lamp Y of signal LHAC or LHBC depending on the position of the switch W. If the switch is in its normal position, energy is supplied to the lamp Y of signal LHAC over the circuit which is traced from terminal B through front contact 69 of relay COSR, front neutral contact 94 and normal polar contact 95 of relay HR, front neutral contact 87 and normal polar contact 88 of relay WP, and yellow lamp Y of signal LHAC to terminal C.

If the switch is in its reverse position, the yellow lamp of signal LHBC is lighted instead of the yellow lamp of signal LHAC. The circuit for the lamp of signal LHBC is the same as that for the yellow lamp of signal LHAC except that it includes reverse polar contact 88 of relay WP instead of the normal polar contact.

At this time polar contact 84 of relay WP establishes a circuit to light the red lamp of the one of the signals LHAC and LHBC which does not have its yellow lamp lighted, while contacts 82 and 75 of relay COSR interrupt the circuits which they control for supplying energy to the red lamps of signals LHAC and LHBC. In addition, contact 75 of relay COSR establishes the circuit to supply energy to relay COP so that alternating current indication energy is supplied to the office to notify the operator that one of the call-on signals is displaying a proceed indication.

When the operator wishes to cancel the call-on signal, he returns the signal control lever to its intermediate position. This deenergizes the relay P and cuts off the supply of direct current of normal polarity over the wire Y to relay HR and its neutral contacts release so that contact 92 interrupts the circuit of the holding winding of relay COSR. As the relays COSR and HR are released, all of the call-on signals display stop indications, while the circuit of the relay COP is interrupted so that alternating current signal indication energy is no longer supplied to the office.

From the foregoing, it will be seen that the modification shown in Fig. 2, like that shown in Fig. 1, provides means to control the call-on signals by supplying alternating current over the same wire that direct current of one polarity or the other is supplied to control the main signals. It will be seen also that the systems of this invention provide means to transmit an indication of the response of the call-on signals over the same wire that indications of the condition of main signals are transmitted.

While the call-on signal control means provided by this invention is arranged particularly for use with the remote control system shown in the patent to Vantassel, the means provided by this invention is not limited to use in this manner but may be employed in other situations.

Although I have herein shown and described only two forms of signal control apparatus embodying my invention, it is understood that various changes and modifications may be made

therein within the scope of the appended claims without departing from the spirit and scope of my invention.

Having thus described my invention, what I claim is:

5. 1. In combination, a section of railroad track, a first main signal and a first call-on signal governing movement of traffic in one direction through said track section, a second main signal and a second call-on signal governing movement of traffic in the other direction through said track section, a polarized signal control relay which when energized with current of normal polarity may cause the first main signal to provide a proceed indication and which when energized by current of reverse polarity may cause the second main signal to provide a proceed indication, a line circuit for supplying energy to said polarized relay, means for at times supplying energy of normal polarity and at other times supplying energy of reverse polarity to said line circuit, means for also supplying alternating current to said line circuit, a first and a second auxiliary relay, a circuit including a back contact of the second auxiliary relay and an asymmetric unit poled to permit flow of energy of normal polarity for supplying energy from said line circuit to said first auxiliary relay, a circuit including a back contact of the first auxiliary relay and an asymmetric unit poled to permit flow of energy of reverse polarity for supplying energy from said line circuit to said second auxiliary relay, a stick relay, each auxiliary relay being effective when picked up to establish a circuit for supplying from the line circuit to the stick relay through a rectifier energy impulses of the polarity other than that of the impulses supplied to such auxiliary relay, said stick relay being effective when picked up providing either of said auxiliary relays is picked up to establish a holding circuit to maintain itself picked up, a circuit controlled by said stick relay and said first auxiliary relay for causing the first call-on signal to provide a proceed indication, and a circuit controlled by said stick relay and said second auxiliary relay for causing the second call-on signal to provide a proceed indication.
2. In a remote control system, in combination, 50 a control office, a first and a second line circuit connecting the control office with a remote station, a first and a second traffic controlling device at the remote station, means at the office for at times supplying direct current energy to said first line circuit, means at the office for at times supplying alternating current energy to said first line circuit, a first relay at the station responsive to direct current supplied over said first line circuit and controlling said first traffic controlling device, a second relay at the station responsive to alternating current supplied over said first line circuit and controlling said second traffic controlling device, means governed in accordance with the condition of the first traffic controlling device for supplying direct current to said second line circuit, means governed in accordance with the condition of the second traffic controlling device for supplying alternating current to said second line circuit, and indication means at the office selectively responsive to direct and alternating current supplied over said second line circuit.
3. In a remote control system, in combination, 55 a control office, a first and a second line circuit connecting the control office with a remote station, a first and a second traffic controlling device at the remote station, means at the office for at times supplying direct current energy to said first line circuit, means at the office for at times supplying alternating current energy to said first line circuit, a first relay at the station responsive to direct current supplied over said first line circuit and controlling said first traffic controlling device, a second relay at the station responsive to alternating current supplied over said first line circuit and controlling said second traffic controlling device, means governed in accordance with the condition of the first traffic controlling device for supplying direct current to said second line circuit, means governed in accordance with the condition of the second traffic controlling device for supplying alternating current to said second line circuit, and indication means at the office selectively responsive to direct and alternating current supplied over said second line circuit.

tion, a first and a second traffic controlling device at the remote station, means at the office for at times supplying direct current energy to said first line circuit, means at the office for at times supplying alternating current energy to said first line circuit, a first relay at the station responsive to direct current supplied over said first line circuit and controlling said first traffic controlling device, a second relay at the station responsive to alternating current supplied over said first line circuit and controlling said second traffic controlling device, means governed in accordance with the condition of the first traffic controlling device for supplying direct current to said second line circuit, means governed in accordance with the condition of the second traffic controlling device for supplying alternating current to said second line circuit, an indication lamp at the office, means at the office responsive to direct current energy supplied over said second line circuit for establishing a circuit to steadily energize said lamp, and other means at the office responsive to alternating current energy supplied over said second line circuit for establishing a circuit to intermittently energize said lamp.

4. In a remote control system, in combination, a control office, a first and a second line circuit connecting the control office with a remote station, a section of railroad track, a first main signal and a first call-on signal governing movement of traffic in one direction through said track section, a second main signal and a second call-on signal governing movement of traffic in the other direction through said track section, a polarized relay at the station energized over said first line circuit and which when energized with current of normal polarity may cause the first main signal to provide a proceed indication and which when energized with current of reverse polarity may cause the second main signal to provide a proceed indication, means at the office for at times supplying direct current of normal polarity and at other times supplying direct current of reverse polarity to said first line circuit, means at the office for also supplying alternating current to said first line circuit, a call-on control relay at the station responsive to alternating current supplied over said first line circuit for causing the first or the second call-on signal to provide a proceed indication according as direct current of normal or reverse polarity is supplied to said first line circuit, a first repeater relay which is deenergized when either the first main signal or the first call-on signal displays a proceed indication, a second repeater relay which is deenergized when either the second main signal or the second call-on signal displays a proceed indication, a slow pick-up relay, means effective on release of either the first or the second repeater relay when the call-on control relay is energized for applying energy to said slow pick-up relay, means including back contacts of said slow pick-up relay and of said first repeater relay for supplying direct current of normal polarity to said second line circuit, means including back contacts of the slow pick-up relay and of the second repeater relay for supplying direct current of reverse polarity to said second line circuit, means including a front contact of said slow pick-up relay for supplying alternating current to said second line circuit, a first, a second and a third indication relay at the control office, a circuit including a back contact of the second indication relay and an asymmetric unit poled to permit flow of energy of normal polarity for supplying energy from said second line circuit to the first indication relay, a circuit including a back contact of the first indication relay and an asymmetric unit poled to permit flow of energy of reverse polarity for supplying energy from said second line circuit to the second indication relay, the first and second indication relays each being effective when picked up to establish a circuit to supply energy from said second line circuit through a rectifier to the third indication relay, means controlled by a circuit including a front contact of the first indication relay and a back contact of the third indication relay for providing a first indication, means controlled by a circuit including a front contact of the second indication relay and a back contact of the third indication relay for providing a second indication, means controlled by front contacts of the first and third indication relays for providing a

5 10 15 20 25 30 35 40 45 50 55 60 65 70 75

tion relay being responsive only to energy of the reverse polarity, the third indication relay being responsive to alternating current energy, each of said indication relays being effective when energized to provide a distinctive indication at the control office.

5. In a remote control system, in combination, a control office, a first and a second line circuit connecting the control office with a remote station, a section of railroad track, a first main signal and a first call-on signal governing movement of traffic in one direction through said track section, a second main signal and a second call-on signal governing movement of traffic in the other direction through said track section, a polarized relay at the station energized over said first line circuit and which when energized with current of normal polarity may cause the first main signal to provide a proceed indication and which when energized with current of reverse polarity may cause the second main signal to provide a proceed indication, means at the office for at times supplying direct current of normal polarity and at other times supplying direct current of reverse polarity to said first line circuit, means at the office for also supplying alternating current to said first line circuit, a call-on control relay at the station responsive to alternating current supplied over said first line circuit for causing the first or the second call-on signal to provide a proceed indication according as direct current of normal or reverse polarity is supplied to said first line circuit, a first repeater relay which is deenergized when either the first main signal or the first call-on signal displays a proceed indication, a second repeater relay which is deenergized when either the second main signal or the second call-on signal displays a proceed indication, a slow pick-up relay, means effective on release of either the first or the second repeater relay when the call-on control relay is energized for supplying energy to said slow pick-up relay, means including back contacts of said slow pick-up relay and of said first repeater relay for supplying direct current of normal polarity to said second line circuit, means including back contacts of the slow pick-up relay and of the second repeater relay for supplying direct current of reverse polarity to said second line circuit, means including a front contact of said slow pick-up relay for supplying alternating current to said second line circuit, a first, a second and a third indication relay at the control office, a circuit including a back contact of the second indication relay and an asymmetric unit poled to permit flow of energy of normal polarity for supplying energy from said second line circuit to the first indication relay, a circuit including a back contact of the first indication relay and an asymmetric unit poled to permit flow of energy of reverse polarity for supplying energy from said second line circuit to the second indication relay, the first and second indication relays each being effective when picked up to establish a circuit to supply energy from said second line circuit through a rectifier to the third indication relay, means controlled by a circuit including a front contact of the first indication relay and a back contact of the third indication relay for providing a first indication, means controlled by a circuit including a front contact of the second indication relay and a back contact of the third indication relay for providing a second indication, means controlled by front contacts of the first and third indication relays for providing a

third indication, and means controlled by front contacts of the second and third indication relays for providing a fourth indication.

6. In combination, a section of railroad track, a first main signal and a first call-on signal governing movement of traffic in one direction through said track section, a second main signal and a second call-on signal governing movement of traffic in the other direction through said track section, a polarized signal control relay which when energized with current of normal polarity may cause the first main signal to provide a proceed indication and which when energized with current of reverse polarity may cause the second main signal to provide a proceed indication, a line circuit for supplying energy to said polarized relay, means for at times supplying energy of normal polarity and at other times supplying energy of reverse polarity to said line circuit, means for at times also supplying alternating current to said line circuit, a stick relay, a transformer, means including a front neutral contact of said polar relay for applying energy from said line circuit to the primary winding of said transformer, means for supplying energy from the transformer secondary winding through a rectifier to said stick relay, a holding circuit including a front contact of said stick relay and a front neutral contact of said polar relay for also supplying energy to said stick relay, and circuits controlled by said stick relay and by polar contacts of said polar relay for causing said call-on signals to provide proceed indications.

7. In a remote control system, in combination, a control office, a first main signal and a first call-on signal at a remote station and controlling movement of traffic in one direction through a stretch of railroad track, a second main signal and a second call-on signal at the remote station and controlling movement of traffic in the other direction through said track stretch, a line circuit connecting the control office with the remote station, a supply transformer at the control office having its secondary winding included in series with said line circuit, a manually operable switch biased to a position in which it causes alternating current to be supplied to said primary winding, means for at times supplying direct current of normal polarity and at other times supplying direct current of reverse polarity to said line circuit, a polarized signal control relay at the remote station energized over said line circuit and which when energized

with current of normal polarity may cause the first main signal to provide a proceed indication and which when energized with current of reverse polarity may cause the second main signal to provide a proceed indication, a stick relay, means effective only when alternating current is supplied to said line circuit to supply energy from said line circuit to said stick relay, a holding circuit for said stick relay including its own front contact and a front contact of a relay responsive to direct current supplied over said line circuit, and means governed by said stick relay and by the polarity of the direct current supplied over said line circuit for controlling said call-on signals.

5 8. In a remote control system, in combination, a control office, a first main signal and a first call-on signal at a remote station and controlling movement of traffic in one direction through a stretch of railroad track, a second main signal and a second call-on signal at the remote station and controlling movement of traffic in the other direction through said track stretch, a line circuit connecting the control office with the remote station, means for at times supplying direct current of normal polarity and at other times supplying direct current of reverse polarity to said line circuit, a first transformer at the control office having its secondary winding connected in series with said line circuit, a manually operable switch biased to a position in which it short circuits the primary winding of said first transformer and movable to a position in which it causes alternating current to be supplied to said primary winding, a polarized signal control relay at the remote station energized over said line circuit and which when energized with current of normal polarity may cause the first main signal to provide a proceed indication and which when energized with current of reverse polarity may cause the second main signal to provide a proceed indication, a stick relay, a second transformer at the remote station, means governed by a relay responsive to direct current supplied over said line circuit for supplying energy from said line circuit through said second transformer to said stick relay, a holding circuit for said stick relay including a front contact of said stick relay and a front contact of a relay responsive to direct current supplied over said line circuit, and means governed by said stick relay and by means responsive to the polarity of the direct current supplied over said line circuit and controlling said call-on signals.
